UNITED STATES PATENT OFFICE.

FRANK L. DODGSON, OF ROCHESTER, NEW YORK, ASSIGNOR TO GENERAL RAILWAY SIGNAL COMPANY, OF ROCHESTER, NEW YORK.

TRAIN CONTROL.

Application filed July 18, 1924. Serial No. 726,781.

- This invention relates to train control systems for railroads, and more particularly to such a system of the type commonly known as the intermittent inductive type.
- 5 In accordance with this invention, it is proposed to communicate or transmit controlling influences from the trackway to a moving train by means of an inductive or non-physical action or cooperation between elements located on the train and elements located at spaced points along the trackway, and to impose, by means of the influences so transmitted, a predetermined speed limit, varying in accordance with changes in traffic conditions 10 ahead, which the train can not exceed without an automatic brake application.
- It is advantageous in train control systems to supply the controlling influences with the use of as little electrical energy as possible, 15 particularly in connection with the trackway equipment, in order to minimize the expense of wayside transmission lines, relays and the like, as well as to reduce the power consumption to a minimum. In order to accomplish 20 this, and other desirable objects, it is contemplated in the present invention to employ trackway elements which will operate to change the magnetic circuit of inductive carried elements when brought into close proximity thereto, said trackway elements requiring no energizing current. With such inert 25 track elements, it has been found that a certain relative movement of the track and the car-carried elements must occur in order that an appreciable impulse may be transmitted. 30 From this it is obvious that, if the vehicle passes over a trackway element below some certain low speed, no control influence will necessarily be received. For a safe speed control system, however, it is essential that the 35 safe speed limits should always be set up whenever traffic conditions require it, irrespective of the speed at which the train may pass the controlling track device.
- 40 Also in an intermittent type of train control system, it is desirable to make provision so that, whenever the train stops, it can not thereafter proceed faster than some restricted minimum speed until a resetting or restor-

ing impulse, indicative of safe traffic conditions, has been received. For example, a train may pass a block signal indicating clear, and for some reason come to a stop in the block, and while stopped, a switch may be opened, or a train back into the same block or the next block in advance, setting up danger conditions. In such a case, it will be evident that the interest of safety would best be served by requiring the train that has stopped to proceed at a restricted minimum speed until, 55 upon reaching the end of the block, it comes again under the automatic control of the trackway equipment.

In view of these and other considerations, it is proposed in accordance with this invention to provide automatic apparatus which acts to set up a restricted speed limit both on the reception of a stopping influence from the trackway and also whenever the train comes to a stop, or slows down below some very 60 low speed, such as 3 miles per hour, this minimum speed limit being continued until a resetting impulse is received from the trackway.

By reason of the feature of setting up a 65 minimum speed whenever the train stops, it becomes necessary to eliminate this automatic function of the system whenever the train is travelling in territory not equipped with reset track devices, otherwise the train could not operate in territory not equipped for train 70 control purposes. A further object of the invention, therefore, is to provide suitable means for rendering the car-carried apparatus inactive to impose the minimum speed 75 limit while the train is travelling in un-equippped territory.

A still further object of this invention is to provide means by which the train operator or engineer is forced to acknowledge changes in 80 traffic conditions as indicated by wayside signals, otherwise some penalty or inconvenience is imposed upon the engineer if he fails to acknowledge such signals, thereby stimulating or enforcing his vigilance.

Further objects, advantages, and characteristics of the invention will become apparent as the description of the system progresses.

In describing the invention in detail, reference will be had to the accompanying drawings in which:—

Fig. 1 represents the section of trackway 5 equipped for automatic train control embodying the present invention, the trackway devices and circuits having been diagrammatically shown;

Fig. 2 is a simplified and diagrammatic 10 showing of the car-carried apparatus comprising a part of the speed and distance governed elements;

Fig. 3 shows in a simplified and diagrammatic manner the circuits of the car carried 15 apparatus;

Fig. 4 represents a section of trackway 20 equipped with apparatus for making a change from trackway territory equipped for automatic train control to unequipped territory;

Fig. 5 shows the trackway equipment and 25 a portion of the car-carried apparatus including alternative means for making a change from equipped to unequipped territory.

Trackway apparatus.—Referring first to Fig. 1, a railway track has been represented by the rails 1 divided into blocks by the insulating joints 2; and the block I and the ends of two adjacent blocks H and J have been 30 shown. As the trackway devices and the circuits used in the several blocks are identical, a detailed description of one block only will be given, corresponding elements in the adjacent blocks being referred to by like reference characters having distinctive exponents.

The usual track battery 3, for supplying 40 track circuit current is connected across the rails at the exit end of the block. A direct current track relay 4 of a type well known in railway signalling practice is connected across the rails at the entrance end of each block, receiving its energizing current from the battery 3 through the rails.

Wayside block signals, taking the form of 45 semaphore or light signals, or any other type of signal, are preferably used; and for the purpose of illustration, signals of the semaphore type have been represented in a conventional manner at Z, without attempting to show their control circuits.

A train control operating inductor O is 55 located at one side of the track rails near the exit end of each block and at least at safe braking distance for the maximum speed limit from the wayside signal at the exit end of the next succeeding block. This inductor O comprises a substantially U-shaped iron core 5 having pole pieces 6 and carrying a winding 7. The core 5 is preferably made of laminated iron. The winding 7 of the operating inductor O is normally in a closed 60 circuit of low resistance through the front contact 8 of a line relay 9 which is energized 65 through a circuit identical with the energiz-

ing circuit for relay 9° which may be traced as follows:—from battery terminal C, through the winding of relay 9°, front contact 10 of track relay 4, wire 11, contact 12¹ of track relay 4¹, to battery terminal B.

A train control reset magnet R is located 70 near the exit end of each block on the opposite side of the track rails from the operating inductor O. The construction of this reset magnet is similar to that of the inductor O, 75 except that the windings and cores may be designed for different currents and fluxes. The winding 13 of reset magnet R for the block I is normally energized from the battery 14 through a circuit including the front contact 15¹ of track relay 4¹ of the block J next in advance, as clearly shown in the drawings. When the block J next in advance is occupied and its track relay 4¹ de-energized, the winding 13 of the reset magnet R for the block I 80 is short-circuited, that is, is included in a de-energized closed-circuited of low resistance through the back contact finger 15¹ of the track relay 4¹. In order to reduce the current consumption for the reset magnets, an 85 approach relay of the usual construction, connected in series with the track battery, may be used to close the energizing circuit for the reset magnet only when a train is approaching.

It is obvious that if a train is in the block 90 J, its wheels and axles will shunt the track circuit in the rails and de-energize the track relay 4. This will open contacts 10, 12 and 15, de-energizing relay 9°, and opening the energizing circuit to reset magnet R^o.

Although the reset magnet R has been 95 shown energized with direct current, it is to be understood that alternating current is equally adaptable for this purpose, and may be used in practice when available.

Car-carried apparatus.—A railway vehicle 100 is represented by a pair of wheels and axles 16. This vehicle carries two receiving devices, an operating receiver RO and a reset receiver RR. These receivers are in the form of 105 U-shaped cores, preferably made of laminated iron, the operating receiver RO carrying two windings S and P, and the reset receiver carrying two windings 88 and 89, as plainly shown in the drawings. These receivers are 110 located on the vehicle in position to travel over and in inductive relation to the trackway operating inductor and reset magnets, respectively. The connections to the coils of these 115 receiving devices will be explained as the description progresses. The air-gap between the receiver RO and the operating inductor O is positioned a short distance, such as 3 inches, above the level of the top of the track rails, so as to avoid improper action of crossing 120 rails and the like upon the receiver.

According to the preferred arrangement, 125 the operating inductor O controlling train movement into a given block is located approximately braking distance for the mini-

imum speed limit (assumed to be 20 miles per hour) in the rear of the entrance to said block, in order that a train approaching said block in the occupied or danger condition may be 5 stopped safely short of the entrance to such danger block, if the engineer fails to acknowledge upon passing said inductor. The reset magnet R, associated with each block and controlled by its track circuit, is located 10 in the rear of the corresponding operating inductor O, so as to be first encountered by a passing train.

As shown, the car equipment is organized 15 for movement of the locomotive or other vehicle with one particular end leading, so as to bring the operating receiver RO on the right-hand side of track; but in practice arrangements may be made, by the use of a reversing switch connected to the car wheels or similar 20 means, to change over the connections between the coils of the receivers RO and RR and the car relays, so that the car may be operated either end leading. With such a reversing switch, such as shown, for example, 25 in the application of C. S. Bushnell, Ser. No. 544,561, filed March 17, 1922, the operating receiver is always on one side (shown as the right-hand side) of the car with respect to its direction of movement. When the car is 30 travelling opposite to the normal direction of traffic, the reset magnets R will not act upon the operating receiver RO, because for such train movement these reset magnets are on closed circuit. For single track railroads, 35 duplicate sets of operating inductors and reset magnets are used for traffic in opposite directions, the set for each direction being controlled in accordance with the indications of the corresponding block signals.

40 Fig. 2 is a simplified showing of a part of the car-carried equipment. A drive shaft 17 is geared to or driven by other suitable means from the wheels of the vehicle. Mounted on this shaft 17 is a centrifugal speed-responsive 45 device or centrifuge G. This centrifuge G may take any one of a number of preferred forms, but is illustrated in a simplified form for the sake of clarity. A fixed collar 18 and a slotted movable collar 19 are mounted on 50 the shaft 17 and are urged apart by the spring 20. The collars are connected by links 21, 22, 23 and 24, carrying weights 25 and 26 as shown. The slotted collar 19 engages the end of a lever 27 which is connected to a speed 55 shaft 28. It is obvious that as the speed of the vehicle increases, the weights 25 and 26 will be thrown outwardly, depressing collar 19 and drawing down the arm 27 against the 60 action of the spring 20, thus rocking the speed shaft 28.

The speed shaft 28 is used to open and close a number of contacts for different ranges of speed. A typical speed contact unit is shown in Fig. 2, and comprises a pair 65 of contacts 146, one of which is a resilient

finger, tending to move away from a stationary contact, represented by an arrow. The resilient finger carries a roller, bearing against the edge of a cam 62. It is evident that by properly shaping the edge of the cam 70 62, the contacts may be closed for any desired range of speeds and opened at other ranges. The unit shown in Fig. 2 is adapted to close its contacts for speeds from zero to 5 miles 75 per hour.

Rigidly secured to the drive shaft 17 is a worm gear 30 engaging a worm wheel 31 which is rigidly secured to a shaft 32. A pinion 33 fixed on the shaft 32 engages two large gear wheels 34 and 35 carried on fixed 80 pins or shafts 36 and 37. Two bifurcated arms 38 and 39 are also journaled on the pins 36 and 37, these arms carrying pinions 40 and 41 which engage the worm wheels 34 and 35, respectively. The free ends of the arms 39 85 and 38 are held down by a cam starter magnet CS and by a distance starter magnet DS, respectively, against the upward pull exerted by two springs 42 and 43. Directly over and in alignment with the pinions 40 and 41 are 90 two mutilated gears 44 and 45. When the magnets DS and CS are deenergized, the arms 38 and 39 are lifted by the springs 42 and 43, and the pinions 40 and 41 engage the mutilated gears 44 and 45, driving them from 95 the drive shaft through the gear train just described.

The mutilated gear 45 drives a shaft 46 carrying a permissive speed cam 47 which operates the upper end of a floating lever 49, the opposite end of which is operated from the speed shaft 28 through a lever 50. It will be seen that the movement of the floating lever 49 just described is dependent on a function of the speed of the vehicle and the distance it has traveled from the point at which the cam-starter magnet CS was deenergized. A specially shaped speed-distance cam 51 is connected by a link 52 to a point near the middle of the floating lever 49. This cam 51 100 is biased by a spring 53 and operates contacts 54 and 55 which are connected in control circuits as hereinafter described. The mutilated gear 44 drives a distance shaft 56. 105

The distance shafts 46 and 56 are used to 110 open and close a number of contacts at different distances of travel from the point at which these shafts are started by the deenergization of their magnets CS or DS. One 115 distance contact unit is shown on each of these shafts in Fig. 2. Each distance unit comprises a pair of contacts, consisting of a resilient finger tending to move away from a stationary finger, the resilient finger carrying 120 a roller which bears against the edge of a cam as shown. By properly shaping the edge of the cam, the contacts may be opened at any 125 distance of travel from the point at which the associated distance shaft was started. The distance contact unit 48 on the shaft 46 130

is adapted to open its contacts immediately on the initiation of the distance shaft 46, while the unit 57 is adapted to open its contact at a point about 1000 feet of car travel from the point at which the distance shaft 56 was initiated. The shafts 56 and 46 are returned to their normal positions by means of the springs 58 and 59.

Referring now to Fig. 3, a diagrammatic view of the car circuits and devices has been shown. The secondary coil S of the operating receiver RO operates a primary relay PT and a secondary relay ST. These relays are preferably of the quick acting type having movable armatures centrally pivoted which are biased by springs 158 and 159 as shown to move from the horizontal attracted position to an inclined retracted position indicated by dotted lines. These armatures when retracted open front contacts shown conventionally as arrows. A reset relay RT is connected to the reset receiver RR and a cam control relay is provided, being connected as hereinafter described. These relays have double centrally-pivoted armatures 60 and 61, similar to the armatures of the relay PT, the opposite ends of which are insulated from each other by the insulating blocks 60¹ and 61¹.

An acknowledging relay Ack, a non-control relay NC, a penalty relay PR, and a low speed relay LS are also provided. These relays, as well as the relays PT, ST, CC and RT, are of a type suitable for train control practice, and are provided with normally biased contacts so mounted as to be unaffected by the vibration or swaying of the train.

Mounted on the speed shaft 28 which is represented in Fig. 3 by a dot-and-dash line, are seven speed cams 62 to 68, inclusive. These cams close contacts at different ranges of speeds, the speeds at which the several contacts are held closed being indicated on the drawings. The distance shaft 46 carries three distance cams 69, 70 and 48. These distance cams are designed to close or open contacts after a certain distance of travel from the point at which the cams are started, as will be hereinafter explained. The distance cam 57 carried on the shaft 56 operates to open contacts 71 and 72 after the vehicle has moved a given distance, assumed to be 1,000 feet, from the point at which this cam 57 is started.

An electro-pneumatic valve EPV is provided for the purpose of applying the brakes in response to certain control influences. This electro-pneumatic valve EPV may be of any suitable type and is preferably of the type which acts to apply the brakes when the circuit thereto is broken. This may be done by venting the brake pipe directly, by moving the regular engineer's brake valve, or in any other suitable manner, but the control of the electro-pneumatic valve is preferably so ar-

ranged that it cannot be operated manually by the engineer.

Car circuits.—For convenience and in order to simplify the drawing, the letters B and C have been used to indicate battery terminals of different polarity. All circuits have been shown in their normal condition, that is, the positions of all contacts and cams are those which would be assumed with the vehicle running above the minimum but below the maximum speed limit, and under clear traffic conditions ahead.

The penalty relay PR is normally energized through a stick circuit which may be traced as follows:—from the battery terminal C, 80 through primary winding P, wire 73, through the winding of penalty relay PR, wire 74, contact 75 of penalty relay PR, wires 76 and 77, contacts 78 of speed cam 65, wires 79 and 80, contacts 71 and 72 of distance cam 57, wire 85 81 to movable contact 82 of secondary relay ST which is connected to battery terminal B.

It should be noted that, as the penalty relay PR is energized through a stick circuit including the primary winding P of the operating receiver RO, a break in the primary winding circuit will cause the deenergization of the penalty relay PR, and an automatic brake application will result as hereinafter described. Thus a check is maintained on the primary winding P against the opening of its circuit.

The secondary winding S of the operating receiver RO is connected to the winding of primary relay PT through a stick circuit 100 which is obvious from the drawings.

The reset receiver RR has two windings 88 and 89 connected in series; and these windings are directly connected to the winding of the reset relay RT through wires 148, 149, 90 and 91. The movable contact 97 of the reset relay RT closes a circuit through the winding of this relay, as clearly shown in the drawings. This circuit comprises the winding of the relay RT and the contacts 97 of this relay in series, and does not include any source of energy aside from the energy stored in the magnetic field set up in this relay RT. In other words, when the relay RT is picked up in response to an influence transmitted from the trackway, this relay closes its contact 97 thereby short-circuiting its winding and thus causing this relay to be slow to drop, that is, this relay will be held up until the energy stored in its magnetic field has been dissipated in the short-circuited winding of the relay.

The low speed relay LS is energized through a pick-up circuit which may be traced as follows:—from battery terminal B, through contacts 98 of distance cam 48, wires 99 and 100, winding of low speed relay LS and wire 101 to battery terminal C. A stick circuit for this low speed LS may be traced as follows:—from the battery terminal C, through the winding of low speed relay LS, 130

wires 101, 100 and 102, contact 103 of relay LS, wire 104, contacts 105 of speed cam 66 to the battery terminal B.

The cam control relay CC is normally energized through a circuit which may be traced as follows:—from the battery terminal B, contact finger 82 and front contact of the secondary relay ST, wire 135, front contacts of the relay CC, wire 94, the winding of the relay CC, wire 95, contacts 96 of the cam 63 to the battery terminal C.

The electro-pneumatic valve EPV is normally energized through a circuit which may be traced as follows:—from battery terminal C through the winding of the electro-pneumatic valve EPV, wires 106 and 107, contact 108 of the penalty relay PR, contact 109 of low speed relay LS, wire 110 and contacts 54 and 55 of the speed-distance cam 51 to battery terminal B.

The remainder of the car circuits will be apparent or pointed out as the operation of the system is explained.

Operation.

Maximum speed limit under clear traffic conditions.—When a train is operating under the control of the system as shown under clear traffic conditions ahead, a maximum speed limit, assumed to be 60 miles per hour, is imposed. Referring to Fig. 2, it is evident that with the permissive speed cam 47 in the position shown, the train speed cannot exceed a certain amount, depending on the radius of this cam, without opening the contacts 54 and 55 and so causing an automatic brake application by the deenergization of the electro-pneumatic valve EPV. The permissive speed cam 47 and the speed distance cam 51 are assumed to be so designed and proportioned that this automatic brake application will occur at a speed of 60 miles per hour. When the train speed drops below the maximum speed limit, the engineer may release the brakes on account of the re-energization of the electro-pneumatic valve EPV through the contacts 54 and 55.

Entering a caution block.—Assuming that a train is located in the block J, the track current in block J is cut off by the wheels and axles of said train, and hence the track relay 4¹ at the entrance end of this block is deenergized and will open its front contacts 10¹, 12¹ and 15¹. The opening of contact 12¹ deenergizes the line relay 9⁰ at the exit end of block II, opening its contact 8⁰, and thus breaking the circuit through the coil of operating inductor O. Reset magnet R⁰ at the end of the block H is then energized through a circuit which is apparent from the drawings.

A following train first passes over the energized reset magnet R⁰. The flux from this magnet will pass through the core of reset receiver RR, energizing its coils 88 and 89, and momentarily energizing the reset relay

RT through a circuit which is obvious. The armature 60 of the reset relay RT will be attracted, but there will be no further effect on the car apparatus, as the cam control relay CC is already energized as shown in Fig. 3.

The train will next pass over the operating inductor O. As the circuit through the coil 7⁰ is open, the inductor acts as an iron bar momentarily placed across the poles of the operating receiver RO. This momentarily reduces the reluctance of the magnetic circuit through the core of the operating receiver, causing a surge of flux in this core. This increase or surge of flux will, according to well-known laws of electricity, induce an electro-motive-force in the coil S, tending to oppose the current normally flowing in this coil and in relay PT connected thereto, and so cause a momentary reduction of the value of this current. The primary relay PT is so adjusted that this momentary reduction of current through it causes it to release its armature 111 and so break its stick circuit, and also the circuit through the winding of secondary relay ST. As the operating receiver RO passes away from the operating inductor O, there is a reduction of flux in the core of receiver RO and a corresponding increase in electro-motive-force in the coil S, but since the primary relay PT has opened its stick circuit, this induced electro-motive-force will have no effect.

The deenergization of the secondary relay ST causes its armature 82 to be retracted and so deenergizes the cam control relay CC, releasing its armature 61, the energizing circuit for the relay CC having been traced above. This breaks a circuit to the cam starter magnet CS clearly shown in the drawings, and starts the cams 69, 70, 47 and 48 in a manner pointed out above.

The deenergization of the secondary relay ST also makes a break in the stick circuit for the penalty relay PR which circuit has been traced above. If, however, the engineer has recognized the wayside caution signal and is diligent, he depresses the push button PB and so energizes the acknowledging relay Ack through a circuit which is clearly shown, such energization of the acknowledging relay Ack completing an alternative circuit through the penalty relay PR which may be traced as follows:—starting at battery terminal C, through primary coil P of operating inductor RO, wire 73, winding of penalty relay PR, wire 74, contact 75 of the penalty relay, wire 76, front contact 112 of acknowledging relay Ack, wires 113 and 80, contacts 71 and 72 of distance cam 57, wire 114, contact 115 of acknowledging relay Ack to battery terminal B.

If the engineer recognizes the caution signal, and operates the push button PB before passing the active inductor O⁰, the penalty relay PR is maintained energized in spite of

the opening of front contact 82 of the secondary relay ST. The engineer must operate the push button before the secondary relay ST is deenergized, otherwise the stick circuit of the penalty relay PR is opened; and in this case the penalty relay cannot be re-energized to permit a release of the brakes until the train is stopped, as hereinafter described. Therefore, the engineer must at all times 10 keep alert and watch the trackway for the indications of the block signals.

After the train has traveled a short distance, such as 100 feet, the distance shaft 46 is turned far enough so that the distance cam 15 70 closes its contacts 86 and 87, establishing a pick-up circuit for the primary relay PT. Attraction of the armature of the primary relay PT as will hereinafter be described re-energizes the secondary relay ST. The engineer must keep the acknowledging relay Ack energized during this distance of travel, or until the secondary relay ST is re-energized to establish the normal stick circuit for the penalty relay PR. The cam control relay 20 25 CC remains deenergized, since its normally closed energizing circuit through the front contacts of the secondary relay ST is opened at its own front contact.

If for any reason the engineer has failed to 30 acknowledge the caution signal the penalty relay PR becomes deenergized, opening its front contact 108, and so deenergizing the electro-pneumatic valve EPV, thereby applying the brakes and bringing the train to a stop. After the train has been brought to a 35 stop, the contacts 116 of the speed cam 64 are closed, and the penalty relay PR may be re-energized through the following circuit:—beginning at battery terminal B, through contacts 116 of speed cam 64, wire 117, winding of penalty relay PR, wire 73, primary coil B of operating inductor RO to battery terminal C. The normal circuit through this penalty 40 45 relay traced above, will not be closed, because the speed contacts 78 are open at the low speed of less than one mile per hour at which speed contacts 116 are closed. It therefore behooves the engineer to operate the acknowledging push button PB to energize the relay Ack, which relay if once energized will 50 55 remain energized so long as the train speed does not exceed 5 miles per hour through the stick circuit including speed contacts 146, thus maintaining the contacts 112 of the relay Ack closed. With contacts 112 closed the relay PR will, if once picked up, be stuck up through the following circuit:—beginning at the terminal of a battery, contact 82 of the relay ST, wire 81, distance contacts 71—72, 60 65 wires 80 and 113, contact 112 of relay Ack, wire 76, stick contact 75, wire 74, winding of the relay PR, wire 73, primary coil P to the common return wire C connected to the other terminal of said battery. From this it will 65 appear that if the speed of the train is grad-

ually increased the speed contacts 78 are closed as soon as the speed of the train is above 3 miles per hour, thus shunting the contacts 112 of relay Ack and re-establishing the normal stick circuit for the relay PR 70 shown closed in Fig. 3. It also appears if the train speed is further increased that the contacts 146 will open when the train speed exceeds 5 miles per hour thus breaking the stick circuit for the relay Ack, thus causing de-energizing of this relay Ack and opening of contacts 112. It should be noted that the increase in train speed to five miles per hour or over must be accomplished within 1,000 feet of travel after the energization of Ack, since as will appear below, at the end of 1,000 feet of travel after DS is deenergized, 71, 72 will be opened to again de-energize PR. This condition results from the fact that the energization of Ack raises 115, causing the de-energization of DS and the opening of 71—72 after 1,000 feet of travel of the vehicle (as described below). It is to be understood, also, that the increase in train speed to five miles per hour or over must not be accomplished 90 within less than 100 feet of travel from the point at which Ack is energized, since the pick-up circuit for PT cannot be closed until contacts 86—87 have become closed. The pick-up circuit for PT will be traced presently. 95

In order that the engineer may not abuse the use of the acknowledging device by holding or fastening the push button PB down, a distance operated cam 57, operating contacts 71 and 72, is provided. When the acknowledging relay Ack is energized, the back contact of its finger 115 opens, deenergizing the distance starter magnet DS through a circuit which is clearly shown in the drawings. This starts the distance cam 57 which, after 1,000 feet of travel, opens the contacts 71 and 72, thus breaking the normal stick circuit for the penalty relay PR and causing an automatic brake application as described 105 above. 110

After a given distance of travel in caution territory, assuming the engineer to have pressed the acknowledging push button PB, assumed to be 100 feet from the point at which 115 the distance cams were started, the cam 70 closes its contacts 86 and 87, re-energizing the primary relay PT through a circuit which may be traced as follows:—from the battery terminal C, through secondary winding S of 120 the operating receiver RO, wire 83, winding of the primary relay PT, wires 84 and 85, contacts 86 and 87 of the distance cam 70, to the battery terminal B. The secondary relay ST will also be re-energized attracting the armature 82 and closing the stick circuit to the penalty relay PR. 125

The train will now proceed in the caution block with the permissive speed cam 47 revolving, and so imposing a tapered speed re- 130

striction on the train as defined by the shape of this cam.

Leaving caution block.—If, when the train approaches the exit end of block I, there is no train in the next two succeeding blocks, the reset magnet R will be energized, and as the reset receiver RR passes over this energized reset magnet, a current is induced in the coils 88 and 89 of this receiver. This induces a current in the reset relay RT, attracting its armature 60 and re-energizing the cam control relay CC through a circuit which may be traced as follows: from the battery terminal B, through the movable contact 92 of the reset relay RT, wires 93 and 94 through the winding of the cam control relay CC, wire 95, contacts 96 of the speed cam 63 to battery terminal C. The contacts 97 of the reset relay RT short-circuit the windings of this relay when the armature 60 is attracted, thus making this relay slow acting so that it will not release before the cam control relay CC has attracted its armature and is energized through its stick circuit. The re-energization of the cam control relay CC causes its armature to close its contact 118 and re-energizes the cam starter magnet CS through a circuit which is clear from the drawings. The pinion 41 will now be released from the mutilated gear 45, and the spring 58 will return the distance shaft 46 to its normal position. The train may now proceed under a maximum speed restriction until further changes in traffic conditions are communicated thereto.

Assume now that the train approaches the end of block I with its controls in the caution position as described above, and that caution conditions exist in the block J. Under these conditions the reset magnet R is energized, and the circuit through the coil 7 of the operating inductor O is open, placing this inductor in the active condition. The reset relay RT is first energized from the reset magnet R through the reset receiver RR, placing the cams in the normal position as just described above. The operating inductor O impresses an impulse on the operating receiver RO and drops the primary relay PT, starting the cams in the same manner in which they were started at the entrance to the caution block and requiring acknowledgment as described above. Thus it is clear that on passing from a danger block to a caution block, the operation of the automatic train control apparatus is the same as its operation on entering the caution block from a clear block, except for the fact that the cams are first set in their normal position before being started by the operating inductor O.

Entering danger block.—Assuming that the train is proceeding under caution control conditions and approaches a block in which another train is located, that is, in which danger traffic conditions exist, the reset

magnet R is deenergized and the cams are not returned to normal. The operating inductor O is in its active condition and acts to drop the primary relay PT, requiring acknowledgment as described above. Thus, on entering a danger block from a caution block, the cams 69, 70, 47 and 48 being already run down, remain down as the train proceeds into the danger block from the caution block, maintaining the minimum speed limit on the train.

On passing from a caution to a danger block, the cam shaft 46 is run down, and its movement cannot be used to restore the primary relay PT to its normal position. When the cam 70 is run down, its contacts 86 and 87 are open, but due to the difference in radii of the concentric portions of this cam, the contacts 86 and 119 are closed; and, if the acknowledging push button PB is depressed, energizing acknowledging relay Ack, the primary relay PT will be re-energized through the following circuit:—starting at battery terminal B, through contact 120 of the acknowledging relay, wire 121, contacts 119 and 86 of cam 70, wires 85 and 84, winding of primary relay PT, wire 83, secondary winding S of operating receiver RO, to battery terminal C.

It should be noted that whenever the primary and secondary relays PT and ST are deenergized, the stick circuit through the penalty relay PR must be maintained closed through a circuit including front contact 115 of the acknowledging relay Ack to prevent automatic brake application and subsequent low speed restriction. In other words, the engineer or train operator must register his vigilance by performing the manual act of acknowledging whenever a caution or a danger signal is passed.

Lowspeed control.—The foregoing description of the operation of the system has been made on the assumption that the train under consideration is travelling above a low speed limit, assumed to be 3 miles per hour. It has been found in practice that the type of receivers described above will not operate successfully below a given low speed. For this reason it is necessary, in order to maintain constant control of the train, to provide means for imposing a low speed limit whenever the train speed is allowed to drop below the safe operating speed of the receivers.

In an intermittent system, wherever a train is brought to a stop at some point in a block, it is considered good practice to restrict the subsequent movement of the train to a minimum speed until an impulse corresponding to clear traffic conditions ahead is received. This is considered desirable for the reason that traffic conditions in the block might have become unfavorable while the train was at a stop. For instance, another train may have entered the block or the block

in advance from a siding, or may have backed into either of these blocks, and these dangerous conditions could not be transmitted to the train under consideration until the track-
5 way inductor at the end of the block was passed.

When the train speed drops below the speed limit below which the reception of an adverse control influence is not relied upon,
10 assumed to be 3 miles per hour, the speed cam 63 will open its contacts 96, deenergizing the cam control relay CC which in turn deenergizes the cam starter magnet CS through circuits which are obvious from the
15 drawings, and starts the distance cams 69, 70, and 48. The speed cam 65 operates to open its contacts 78. This breaks the stick circuit for the penalty relay PR, unless the acknowledging relay *Ack* is operated to close an alternative circuit for the penalty relay through
20 the contact 112. The speed cam 66 operates to open its contacts 105 breaking the stick circuit to the low speed relay LS, which circuit may be traced as follows:—from the battery terminal B, contacts 105 of cam 66, wire 104, contact finger 103 and front contact of the relay LS, wires 102 and 100 and the winding of the relay LS to the battery terminal C. After the distance cam 48 has started and
25 opened its contacts 98, the energizing circuit for the low speed relay LS through these contacts 98 and the wires 99 and 100 is broken, causing the contact fingers 103 and 109 of this relay to drop. This throws the control
30 of the electro-pneumatic valve EPV from contacts 54 and 55 of the speed-distance cam 51 through the wire 122 to the contacts 123 of the speed cam 67. The contacts of the speed cam 67 are maintained closed at train
35 speeds of from zero to 20 miles per hour, so that the train may now proceed under this speed restriction until the distance cams are reset. It should be noted that in order to energize the electro-pneumatic valve through
40 the contacts 123 of the speed cam 67, it is necessary that the contact 124 of the acknowledging relay be closed, provided the speed of the train is below 3 miles per hour. For this reason the acknowledging relay must be
45 maintained energized until the train speed is in excess of 3 miles per hour at which time contacts 125 of speed cam 68 are closed and contacts 125, thus maintaining a circuit through the electro-pneumatic valve
50 which may be easily traced as follows, closed:—starting at the terminal B, contacts 125, contacts 123, back contacts 109, contacts 108, wires 107 and 106, winding of the brake control device EPV, back to the common return wire C. In order that the engineer need
55 not manually maintain the acknowledging relay *Ack* energized until the train speed is above 3 miles per hour, a stick circuit for the acknowledging relay, through contacts 146 of the speed cam 62, closed from zero to 5

miles per hour and front contact of finger 147 of the acknowledging relay *Ack* is provided.

From the above it is evident that, whenever the engineer allows the train speed to drop below 3 miles per hour, the automatic control formerly imposed by cam 51, is rendered inactive, and a new restrictive control is imposed by cam 67. It should also be noted that, in order to avoid the de-energization of the penalty relay PR and an immediate automatic brake application bringing the train to a stop, the engineer must operate the acknowledging push button PB whenever the train speed drops below 3 miles per hour. The restrictive minimum speed limit continues until the train reaches an energized reset magnet which energizes the reset relay RT, and results in the re-energization of the cam starter magnet CS and the restoration of the cams as hereinbefore described. If the cam shaft 46 is restored to its normal position, contacts 98 are closed, establishing a pick-up circuit for the low speed relay LS, which then remains energized through its stick circuit until the speed again drops below 3 miles per hour. When the low speed relay LS is re-energized, the control of the brakes is dependent upon the penalty relay PR and the speed-distance cam 51.

The low speed relay LS and its control as just described, requires that every time the train stops or drops below 3 miles per hour, it cannot thereafter proceed at a speed greater than the minimum speed of 20 miles per hour until the active reset magnet is passed. This means that whenever a train stops in the middle of a block it must run at a restrictive speed to the end of that block where it can encounter an active reset magnet. Ordinarily this does not impose any objectionable restrictions upon the train operation, but on the contrary, for reasons explained above, it is desirable in systems of the intermittent type. Where there are regular stops such as station stops, water tanks, and the like, special release magnets may be provided, if desired, to remove the minimum speed restriction at once without waiting until the train has traveled to the end of the block.

The low speed relay LS and its control, as just described, also facilitates and simplifies the control required to protect trains moving from sidings on to the main track. By reason of the provision of the low speed relay LS, whenever the train stops on a siding, it can not thereafter proceed at a speed greater than the restricted minimum speed until it passes a live reset magnet. Accordingly, a train coming out on to the main track from a siding is automatically restricted to a minimum speed, irrespective of whether the block on the main track is in the clear, caution, or danger condition. Hence it is not necessary

to provide an operating inductor or equivalent means at each siding to assure the safe control of a train leaving that siding.

Entering and leaving non-train control territory.—Referring to Fig. 4 of the drawings, a section of track has been shown equipped for a change from train control territory to territory not equipped for train control. Three blocks K, L and M have been shown, the block K being equipped for train control operation, the block L being equipped for a change from train control to non-train control territory, while the block M is unequipped for train control operation. The equipment of the exit end of block K is identical with the trackway equipment described in connection with Fig. 1, and for this reason a detailed description of this trackway equipment will not be repeated, it being understood that the operation of the track relays, inductors and reset devices is the same as that described in connection with Fig. 1. At the exit end of the block L two spaced non-train control reset magnets CR¹ and CR² are located. These reset magnets are of the same construction as reset magnet R, but are continuously maintained energized by a battery 126. Slightly in advance of the non-control reset magnet CR¹, and on the opposite side of the track rails, is located a non-control operating inductor CO. This non-control inductor CO is of the continuously active type, that is, it is composed of a U-shaped core only, no winding being present. The non-control operating inductor CO is located approximately 100 feet along the trackway from non-control reset magnet CR², for reasons which will be apparent as the description progresses.

Assuming a train to be travelling in block L at speed, that is above the low speed limit assumed to be 3 miles per hour and below the high speed limit assumed to be 60 miles per hour, the car-carried reset receiver RR first passes over the energized non-control reset magnet CR¹. This operates in a manner described above to reset the distance cams 69, 70, 47 and 48, so placing the car-carried apparatus in its normal condition. If the distance cam shaft 46 is already in its normal position, the reset magnet CR¹ will have no effect on the car-carried apparatus. The operating receiver RO next passes over the active non-control operating inductor CO, which starts the distance cams in operation through circuits and relays which have been described. After 125 feet of travel, the contacts 127 of the distance cam 69 will be closed. It should be noted that at this point the primary relay PT and the secondary relay ST have been re-energized through the closing of the contacts 86 and 87 of the distance cam 70, which contacts close after 100 feet of car travel from the point at which the cams are started as explained above. At this point the

reset receiver RR will be energized from the non-control reset magnet CR², and the reset relay RT and the cam control relay CC will be energized. If at this point the acknowledging relay Ack is energized by depressing the push button PB, a circuit through the non-train control relay NC will be closed. This circuit may be traced as follows:—from the battery terminal C, through the winding of the non-control relay NC, wires 128 and 129, contact 130 of the acknowledging relay, wire 131 through the contacts 127 of the distance cam 69, wire 132 and contact 118 of the cam control relay CC to the battery terminal B. While the energization of the cam control relay CC will cause the energization of the cam starter magnet CS and the subsequent opening of the contacts 127 of the distance cam 69 at the same time that the non-control relay NC is energized, the relay NC is so proportioned and arranged that it will act more quickly than the cam starter magnet, and so will operate its contacts 133 before the energizing circuit of its winding has been broken.

The energization of the non-control relay NC will attract its contact 133, closing a stick circuit through this relay which may be traced as follows:—from the battery terminal C through the winding of the non-control relay NC, wires 128 and 134, contact 133 of the non-control relay NC, wires 144 and 135, through the armature 82 of secondary relay ST to the battery terminal B. The energization of the non-control relay NC closes its contacts 136, 137, and 138. The closing of the contact 136 maintains the stick circuit through the penalty relay PR closed as is evident from the drawings. The closing of the contact 137 maintains the stick circuit of the low speed relay LS closed, regardless of the train speed. The closing of the contact 138 maintains an energizing circuit through the electro-pneumatic valve, and thus prevents an automatic brake application. When the non-control relay NC is energized the cab signal 139 is displayed, indicating to the engineer or train operator that the automatic train control apparatus is no longer in effect. The train may now proceed over trackway not equipped for automatic control without delay by automatic brake application.

Referring now to Fig. 5, the trackway equipment and part of the car-carried apparatus comprising another modification of the means for energizing the non-control relay NC and so rendering the car-carried brake control apparatus inactive has been shown. Referring particularly to the trackway equipment, the block V, and the ends of the adjacent blocks U and W have been shown, the blocks U and V being the last two blocks in a section of trackway which is equipped for automatic train control, and the block W being the first block in an unequipped section

of trackway. The equipment in the blocks U and W is identical with that shown in Fig. 4 described above. At the exit end of the block V, on the left side of the track rails, is located an excess energy reset magnet RE which is similar to the reset magnet R, but is permanently energized with an excess amount of current from the battery 151. For the sake of simplicity, only that portion of the car-
10 carried apparatus which differs from the car-
carried equipment shown in Fig. 3 has been
disclosed in Fig. 5. It is to be understood
that a diagram of the complete car-carried
apparatus embodying the modified method of
15 rendering the brake control apparatus inactive
could be obtained by a combination of
Figs. 3 and 5.

A railway vehicle has been conventionally represented at 152 in the block U, and is
20 equipped with an operating receiver RO and
a reset receiver RR, identical with the car-
carried receivers described in connection with
Fig. 3. The reset receiver RR is connected in
series with the reset relay RT through a cir-
25 cuit which may be traced as follows:—From
the winding 89 of the reset receiver RR, wires
148 and 91, the winding of reset relay RT,
wires 90, 149 and 153, back contact and
contact finger 154 of the acknowledging relay
30 Ack, and wires 155 and 156 to the winding
88 of the reset receiver RR. It will be ob-
served that the contact finger 154 of the ac-
knowledging relay Ack normally shunts the
resistance unit 157, and that when this relay
35 is energized to attract the finger 154, the re-
sistance unit 157 is included in the series cir-
cuit from the reset receiver RR to the reset
relay RT, just traced. The pick-up circuit
for the non-control relay NC is completed
40 through a contact finger 161 of the reset relay
RT, wire 160 and contact finger 130 of the
acknowledging relay Ack as clearly shown
in the drawings, the distance cam 69 and its
associated contact 127 shown in Fig. 3 being
45 omitted in the modification shown in Fig. 5.
All other circuits and devices of the car-car-
ried apparatus shown in Fig. 5 are identical
with those shown in Fig. 3, and as their ar-
rangement and operation has been described
50 above, no further description of these circuits
and devices is necessary.

When a train equipped with the modified
apparatus shown in Fig. 5 approaches the exit
55 end of the block V which is the last block in
a section of trackway equipped for automatic
train control, the engineer, knowing by some
suitable wayside indication that he is ap-
proaching a section of unequipped trackway,
60 depresses the push button PB and so energizes
the acknowledging relay Ack, causing its con-
tact finger 154 to be attracted, and inserting
the resistance unit 157 in the circuit to the
reset relay RT. The reset receiver RR now
65 passes over the excess energy magnet RE and,
as this magnet is supplied with an excess

amount of current, the reset relay RT will
be energized in spite of the resistance offered
by the unit 157 in its energizing circuit, and
the contact finger 161 of the reset relay RT
will be attracted, closing its front contact and
70 completing a pick-up circuit for the non-con-
trol relay NC through the contact finger 130
and the front contact of the acknowledging
relay Ack, which circuit is obvious from the
drawings. Once energized, the non-control
75 relay NC will remain energized through its
stick circuit as hereinbefore described, and
will maintain its contact fingers 133, 136,
137 and 138 attracted, energizing the penalty
relay PR, the low speed relay LS and the elec-
80 tro-pneumatic valve EPV, so that the train
may proceed unrestricted in the unequipped
section of trackway.

If the engineer attempts to release the train
from the restriction of the automatic brake
85 apparatus by depressing the push button PB
while the train is passing over the normally
energized reset magnet R, the resistance unit
157 will be immediately inserted in the circuit
from the reset receiver RR to the reset relay
90 RT, and the energy delivered from the reset
magnet R to the reset receiver RR will not
be sufficient to energize the reset relay RT
because of the presence of this resistance unit
95 in this circuit. It is thus evident that the en-
gineer may render the car-carried brake con-
trol apparatus inactive only when passing
an excess energy reset magnet and, as these
magnets are located only at points where it
100 is desired to travel over unequipped sections
of trackway, the engineer may not avoid the
restrictions of the automatic control when
travelling in equipped territory.

When a train equipped with either of the
105 modified forms of non-control set up shown
in Figures 3 and 5 returns to a section of
trackway equipped for automatic train con-
trol, and passes over an operating inductor
which is in the active condition, the operating
110 receiver RO will be actuated in a manner
hereinbefore described, dropping primary re-
lay PT and the secondary relay ST, and so
breaking the stick circuit to the non-control
relay NC. This will drop the contacts 133,
115 136, 137 and 138, and the train may now pro-
ceed under automatic control in the manner
described.

It may be desirable to place the train con-
120 trol apparatus in an active condition imme-
diately upon the entrance of the train into
equipped territory, before an active oper-
ating inductor is encountered. In this case, a
special inductor, similar to the inductor CO
125 and continuously in an active condition, may
be located at the entrance to each section of
trackway which is equipped for automatic
train control.

It is to be understood that the specific cir-
130 cuits, devices and arrangements shown are
used for the purpose of disclosing the inven-

tion and not for limiting its scope, and that many changes, modifications and improvements might be made without departing from the spirit of the invention. For instance, al-

ternating current may be used for energizing the reset magnet instead of direct current from a battery, as shown, a condenser being preferably connected in series with the winding of said reset magnet in that case.

10 What is desired to be secured by Letters Patent of the United States is:—

1. In an automatic train control system of the type in which control influences corresponding to traffic conditions are inductively transmitted from the trackway to a moving vehicle, car-carried means for controlling the speed of the vehicle in accordance with traffic conditions, and associated means, operated by a car-carried speed responsive device, for imposing a low speed restriction when the speed of the vehicle drops below a predetermined minimum.

2. In an automatic train control system, means for communicating impulses corresponding to traffic conditions from elements located at spaced points along the track rails to inductive car-carried elements; means actuated by said car-carried elements for limiting the speed of the train in accordance with traffic conditions, additional car-carried speed controlled means for bringing the train to a stop whenever the train speed drops below a given minimum value, and manually actuated means, which, if actuated when the train passes below said minimum speed value, will prevent the automatic stopping of the train.

3. In an automatic train control system, means partly located on a vehicle and partly located at spaced points along the track rails for inductively transmitting control influences corresponding to traffic conditions to speed controlling apparatus on the vehicle, further means, controlled by the speed of the vehicle, for bringing the vehicle substantially to a stop if the train speed drops below a given speed, manually actuated means for substituting a low speed limit for said stop, and a distance controlled device for bringing the vehicle to a stop if said manually actuated means is left in an active condition for more than a given distance of vehicle travel.

4. In an automatic train control system, means partly located on a vehicle and partly located at spaced points along the track rails for inductively transmitting control influences corresponding to traffic conditions to speed controlling apparatus on the vehicle, further means for bringing the vehicle substantially to a stop when an influence corresponding to unfavorable traffic conditions is transmitted, manually actuated means for substituting a permissive speed restriction for said stop, and a distance control device

for bringing the vehicle to a stop if said manually actuated means is maintained actuated for more than a given distance of vehicle travel.

5. In an automatic train control system, inductive trackway elements, located at spaced points along both sides of the track rails, said inductive trackway elements on one side of the track rails being normally electrically energized and said elements on the other side of the track rails being normally inert, apparatus carried on a railway vehicle for responding to influences from said trackway elements, and for controlling the movement of the vehicle in response to the influences so received and further means located along the track rails for placing said vehicle carried apparatus in an inactive condition.

6. In an automatic train control system, vehicle-carried apparatus including a permissive speed device normally setting up a permissive speed limit, and when initiated gradually setting up more restrictive speed limits, trackway and vehicle-carried elements for transmitting influences corresponding to traffic conditions to control apparatus for said permissive speed device, speed governed means for bringing the vehicle substantially to a stop when the train speed has been reduced below a given low speed, and further trackway elements acting to render said permissive speed device and said speed governed means inactive while the vehicle is travelling over certain sections of trackway.

7. In an automatic train control system, vehicle-carried apparatus for automatically limiting the vehicle speed, inductive means comprising coils mounted on the vehicle and devices mounted on the trackway for communicating control influences corresponding to traffic conditions to said speed limiting apparatus, said trackway devices comprising normally energized electro-magnets located on one side of the track rails, and inductor elements requiring no energy located on the other side of the track rails, further trackway devices comprising two constantly energized electro-magnets located on one side of the track rails, and a constantly active inductor element located on the other side of the track rails at a point between said two constantly energized electro-magnets, and a predetermined distance of vehicle travel in advance of the second of said inductor elements said further trackway devices acting to render said speed limiting apparatus inactive.

8. In an automatic train control system, car-carried apparatus for normally controlling the progress of a vehicle automatically in accordance with influences corresponding to traffic conditions, means for communicating said influences from the trackway to the moving vehicle, comprising trackway inductive devices and car-carried inductive devices, a car-carried relay, manually operable means

for energizing said relay, further trackway devices comprising two constantly energized magnets located on one side of the track rails and spaced apart, and a constantly active inductor located on the other side of the track rails and at a point between said two constantly energized magnets and a predetermined distance of vehicle travel in advance of the second of said constantly energized magnet, and associated car-carried means, active when said manually operable means is actuated at a point of car travel near said second constantly energized magnet, to render said automatic controlling apparatus 15 active.

9. In an automatic train control system, car-carried apparatus for controlling the movement of a train in accordance with influences corresponding to traffic conditions ahead, trackway and car-carried inductive means for communicating said influences from the trackway to said car-carried apparatus, a stick relay associated with said car-carried apparatus and adapted to drop its contacts under certain control conditions, a cam operated by the distance of travel of the vehicle and initiated by the dropping of said stick relay, said distance cam closing a circuit to re-energize said stick relay after a given distance of car travel from the point at which said stick relay contacts were dropped, and manually actuated means, active after a further distance of travel from the point at which said stick relay contacts were dropped, 35 to re-energize said stick relay.

10. In an automatic train control system, vehicle-carried apparatus including a stick relay for normally controlling the progress of the vehicle automatically in accordance with influences corresponding to traffic conditions, trackway influences from the trackway to the moving vehicle, and for de-energizing said stick relay under certain traffic conditions, a manually energized acknowledging relay associated with said car-carried apparatus, further inductive trackway means for rendering said controlling apparatus inactive of said acknowledging relay is energized while the vehicle is passing said further trackway means, a distance operated device for re-energizing said stick relay at a given distance of vehicle travel from the point at which it was de-energized, and further means, including a front contact of said acknowledging relay, for re-energizing said stick relay after the vehicle has travelled more than said given distance from the point at which said stick relay was de-energized.

11. In an automatic train control system, car-carried apparatus for normally controlling the car speed in accordance with influences corresponding to traffic conditions, car and trackway inductive elements for transmitting said influences to the moving car, a manually energized acknowledging re-

lay, a low speed stick relay, and a penalty relay, associated with said car-carried apparatus, speed governed means, active when the car speed drops below a given minimum, to de-energize said low speed stick relay, and to de-energize said penalty stick relay, means electrically associated with said penalty stick relay for bringing the car to a stop when said penalty stick relay is de-energized, a circuit closed by the energization of said acknowledging relay to prevent the de-energization of said penalty stick relay, and further speed control apparatus being substituted for said normally controlling apparatus by the de-energization of said low speed stick relay. 80

12. In an automatic train control system, car-carried apparatus including a primary stick relay for controlling the progress of the car in accordance with influences corresponding to traffic conditions ahead, inductive elements mounted partly on the car and partly on the trackway for communicating said influences to the moving car, said trackway elements acting to de-energize said primary stick relay under certain traffic conditions, a penalty stick relay, active when de-energized to effect an automatic brake application, bringing the car to a stop, said primary stick relay when de-energized opening a circuit to said penalty stick relay, and an alternative circuit including the front contacts of a manually energized acknowledging relay, for maintaining said penalty stick relay energized when said primary stick relay is de-energized, and thus preventing 100 an automatic brake application.

13. In an automatic train control system for railways having a portion of their trackway equipped for automatic train control and a portion not so equipped, vehicle carried control apparatus for controlling the brakes of a train in accordance with control influences corresponding to traffic conditions ahead, trackway and vehicle carried inductive elements each including an iron core for transmitting said control influences to a moving vehicle, and other trackway elements each including an iron core supplied with an amount of energy in excess of the amount supplied to said first trackway elements, and acting with vehicle carried means to render said vehicle carried control apparatus inactive while the vehicle is travelling in said un-equipped portions of trackway. 110

14. In an automatic train control system, car-carried apparatus for controlling the brakes of a vehicle in accordance with influences corresponding to traffic conditions ahead, means for communicating said influences from the trackway to a moving vehicle 125 comprising trackway inductive devices each including a magnetic core and car-carried inductive devices each including a magnetic core, a car-carried relay for rendering said car-carried brake control apparatus inactive 130

and means for actuating said relay comprising manually controllable car-carried means and a trackway inductive device supplied with an excess amount of energy.

- 5 15. In an automatic train control system, car-carried apparatus for controlling the brakes of a vehicle in accordance with control influences corresponding to traffic conditions, means for communicating said control influences from the trackway to a moving vehicle comprising inductive car-carried devices and spaced inductive trackway devices comprising cores of magnetic material when in their active condition, a car-carried relay active 10 when energized to render said brake control apparatus inactive, manually controllable means for energizing said relay only when an excess amount of energy is supplied to one of said inductive car-carried devices, and a 15 trackway inductive device including a core of magnetic material supplied with an excess amount of energy and acting to communicate an excess amount of energy to one of said inductive car-carried devices, whereby said 20 relay may be energized by said manually controllable means only when the vehicle passes said excessively energized trackway inductive device.

16. In an automatic train control system 30 having a portion of its trackway equipped for automatic control and a portion not so equipped, vehicle carried apparatus including a permissive speed device normally setting up a permissive speed limit and when 35 initiated gradually setting up a permissive speed limit and when initiated gradually setting up more restrictive speed limits, trackway and vehicle carried devices for transmitting influences corresponding to traffic conditions to the vehicle and for controlling said 40 permissive speed device in accordance with said influences, car-carried speed governed means for imposing a constant minimum speed restriction when the train speed has 45 been reduced below a given low speed, and other trackway elements, located at the entrance to said unequipped sections of trackway, and supplied with an excess amount of energy, said other trackway elements acting 50 with manually controllable car-carried means to render said permissive speed device and said speed governed means inactive, whereby said constant minimum speed restriction will 55 not be imposed on a train travelling in said unequipped sections of trackway.

17. In an automatic train control systems 60 for railways having portions of their trackway equipped for automatic train control and portions not so equipped, vehicle carried apparatus including a permissive speed device for gradually setting up more restrictive speed limits when initiated, trackway and vehicle carried inductive devices for transmitting control influences corresponding to traffic conditions to the vehicle and for control-

ing said permissive speed device in accordance with said control influences, car-carried speed governed means for bringing the vehicle substantially to a stop if the train speed is reduced below a given minimum, manually 70 controllable means for substituting a constant minimum speed restriction for said stop, and another trackway inductive device supplied with an excess amount of energy and located at the entrance to said unequipped portions of trackway and acting 75 with said manually controllable means to render said permissive speed device and said speed governed means inactive, whereby said stop or said constant minimum speed restriction are not effective if the train speed is reduced below said given minimum while the train is travelling over said unequipped sections of trackway.

18. In an automatic train control system, 85 trackway and vehicle-carried means for transmitting influences corresponding to traffic conditions to a moving vehicle, vehicle-carried apparatus for causing an automatic brake application and bringing the vehicle 90 to a stop in response to influences corresponding to unfavorable traffic conditions, manually actuatable means for substituting a speed restriction for said stop if actuated before an influence corresponding to unfavorable traffic conditions is received, and a distance controlled device for bringing the vehicle to a 95 stop if said manually actuatable means is maintained actuated for more than a predetermined distance of vehicle travel. 100

19. An automatic train control system comprising, a normally energized electro-responsive brake control device connected in a stick circuit carried by a railway vehicle, means partly on the vehicle and partly along the 105 track for momentarily opening said stick circuit, and manually operable means for preventing opening of said stick circuit when manually operated, and means for restricting the progress of the vehicle if said manually operable means remains manually operated during more than a predetermined limited distance of travel of the vehicle. 110

20. Railway traffic controlling apparatus comprising, normally inactive automatic 115 brake application mechanism on a vehicle, means controlled from the trackway for setting said mechanism into operation under unsafe traffic conditions, and manually controllable means on the vehicle operable only for a limited distance of travel of the vehicle to prevent said mechanism being set into operation from the trackway, and which if operated through more than this limited distance itself effects a brake application. 120

21. In a train control system, train controlled means on a vehicle having a normally closed operating circuit and an auxiliary retaining circuit, and manually operable means for closing the retaining circuit, 125 130

said manually operable means when operated opening the operating circuit after a predetermined distance of travel of the vehicle after such manual operation.

- 5 22. Railway traffic controlled apparatus comprising, brake application means on a vehicle, devices located at intervals in the trackway and arranged to cooperate with said means to cause a brake application in the

event of dangerous traffic conditions ahead, and manually operable means on the vehicle which may be rendered effective only through a given distance of travel of the vehicle to prevent a brake application due to such cooperation. 10

In testimony whereof I affix my signature. 15

FRANK L. DODGSON.
